UNITED STATES PATENT OFFICE

162,667

MACHINE FOR DISPENSING STRIP MATERIAL

Alfred P. Krueger, Stratford, Conn., assignor to Derby Sealers, Incorporated, Derby, Conn., a corporation of Connecticut

Application August 25, 1950, Serial No. 11,931

Term of patent 14 years

(Cl. D74—1)

To all whom it may concern:

Be it known that I, Alfred P. Krueger, a citizen of the United States, residing in Stratford, in the county of Fairfield and State of Connecticut, have invented a new, original, and ornamental Design for a Machine for Dispensing Strip Material, of which the following is a specification, reference being had to the accompanying drawing, forming part thereof, in which

Fig. 1 is a side elevational view of a machine for dispensing strip material embodying my new design;

Fig. 2 is a front elevational view thereof;

Fig. 3 is a top plan view; and

Fig. 4 is a side elevational view showing the side opposite that shown in Fig. 1.

I claim:

The ornamental design for a machine for dispensing strip material, substantially as shown.

ALFRED P. KRUEGER.
